(57) **CLAIM**

The ornamental design for a aerosol container cap, as shown and described.

DESCRIPTION

FIG. 1 is a perspective view of an aerosol container cap, showing our new design;

FIG. 2 is a front elevation view thereof;

FIG. 3 is a right side elevation view thereof;

FIG. 4 is a bottom elevation view thereof;

FIG. 5 is a top elevation view thereof;

FIG. 6 is a perspective view of an aerosol container cap, showing a second embodiment of our new design;

FIG. 7 is a front elevation view thereof;

FIG. 8 is a right side elevation view thereof;

FIG. 9 is a bottom elevation view thereof; and,

FIG. 10 is a top elevation view thereof.

The back elevation views are the same as the front elevation views, and the left side elevation views are the same as the right side elevation views.
